UNITED STATES PATENT OFFICE.

LEWIS E. WACKERLE, OF NORTH CHICAGO, ILLINOIS, ASSIGNOR TO CHICAGO HARDWARE FOUNDRY COMPANY, OF NORTH CHICAGO, ILLINOIS, A CORPORATION OF ILLINOIS.

DESIGN FOR A STAND FOR FISH BOWLS OR SIMILAR ARTICLES.

Application filed March 21, 1929. Serial No. 30,575. Term of patent 3½ years.

To all whom it may concern:

Be it known that I, LEWIS E. WACKERLE, a citizen of the United States of America, residing at North Chicago, in the county of Lake and State of Illinois, have invented a new, original, and ornamental Design for a Stand for Fish Bowls or Similar Articles, of which the following is a specification, reference being had to the accompanying drawing forming a part thereof.

The figure represents a perspective view of a stand showing my new design.

I claim:

The ornamental design for a stand for fish bowls or similar articles, as shown.

LEWIS E. WACKERLE.
